UNITED STATES PATENT OFFICE.

CHANNELL L. SAUNDERS, SR., OF BERWICK, LOUISIANA, ASSIGNOR OF ONE-HALF TO
WALTER T. GILMORE, OF MORGAN CITY, LOUISIANA.

TANK.

1,247,336.

Specification of Letters Patent. Patented Nov. 20, 1917.

Application filed August 26, 1913. Serial No. 786,785.

To all whom it may concern:

Be it known that I, CHANNELL L. SAUNDERS, Sr., a citizen of the United States, residing at Berwick, in the parish of Saint Mary 5 and State of Louisiana, have invented certain new and useful Improvements in Tanks; and I do hereby declare the following to be a full, clear, and exact description of the invention, such as will enable others skilled in 10 the art to which it appertains to make and use the same.

This invention relates to new and useful improvements in tanks and has for its object the provision of a device which will permit 15 the repair of the valves in such tanks without the necessity of emptying the tank of its contents.

Another object of my invention is the provision of such a device which will be separate from the tank and form a well which will form a manhole of sufficient size to permit a workman to enter said well and repair the valve contained in the tank.

With the above and other objects in view 20 I will now proceed to describe my invention in the following specification and accompanying drawings, in which,

Figure 1 is a sectional view through a fragment of a railroad tank showing my improved device applied thereto,

Fig. 2 is a detail sectional view taken on line 2—2 of Fig. 1,

Fig. 3 is an enlarged detail sectional view of the auxiliary valve,

Fig. 4 is a top plan view of a fragment of my improved tank,

Fig. 5 is an enlarged detail sectional view of the outlet valve, and

Fig. 6 is a transverse sectional view taken 40 on line 6—6 of Fig. 5.

Referring to the drawings by characters of reference 1 indicates the bottom of my improved tank, having extending upwardly from the edges thereof the sides 2, these 45 sides being preferably formed of sheet metal and riveted as clearly illustrated in the drawings. A vertically disposed auxiliary wall 3 is secured to the bottom 1, as clearly shown at 4 and terminates at each extremity 50 in the angularly extending walls 5 and 6 which are firmly secured to the wall 3 to form a water tight joint. The opposite ends of the walls 5 and 6 are preferably riveted or otherwise secured to the upstanding 55 wall 2 of the tank, as clearly illustrated

at 7, and are so arranged that no water will be permitted to enter the wall thus formed between the end of the wall 5 and the walls 2. A suitable ladder 8 is secured to the wall 5 as will be clearly seen upon referring to 60 the drawings and is adapted to form a means of ingress from the top of the tank to permit a workman to enter.

Immediately adjacent the lower extremity 65 of the wall 3 and centrally located with relation thereto I preferably provide the aperture 9 through which the water from the tank is adapted to enter the well. A suitable collar 10 is secured to the wall 3 by means of the flanges 11 which are held there- 70 to by means of rivets or other suitable fasteners. This collar 10 extends outwardly, as clearly illustrated, and terminates in an angular valve seat 12, this valve seat being inclined preferably at an angle of substantially 75 45 degrees with relation to the collar and is internally beveled to snugly receive the inwardly extending portion or boss 13 formed on the flap valve 14 which is pivotally secured to an ear 15 formed on the upper 80 portion of the collar 10, as will be clearly seen upon referring to Fig. 3 of the drawings. Adjacent the lower edge of the flap valve at a point substantially diametrically opposite the pivot I preferably provide a 85 loop 16 which is adapted to cooperate with an apertured rod 17 extending upwardly to the top of the tank. This rod is adapted to control the valve when the device is in use.

A suitable aperture 18 is formed on the 90 bottom of the well and communicates with a pipe 19 which is secured to the bottom by means of a flange 20, this flange 20 being adapted to receive rivets or bolts and thereby hold the pipe 19 in position. A collar 21 95 is provided and secured to the bottom wall on the side opposite the pipe 19. The aperture through this collar is adapted to register with the aperture 18 in the bottom and form a passage through which the liquid 100 contained in the tank is adapted to be withdrawn. This collar 21 has a flange 22 formed integral therewith which is adapted to be secured to the bottom by means of any suitable attachment. A valve seat 23 is 105 formed at the upper extremity of the collar and provides a means to form a tight joint between the valve 24 and said collar. Centrally located of this valve 24 I preferably provide the upstanding ears 25 to which is 110

pivotal secured the lever 26, having the downwardly extending angular portion 27 formed at one end thereof. This downwardly extending portion 27 preferably terminates in an apertured member which is adapted to coöperate with the ear 28 and pivotally secure the lever with relation to the bottom of the tank as will be clearly seen upon referring to Fig. 5. The end of the lever opposite the angularly extending member 27 is preferably apertured as clearly illustrated and adapted to coöperate with a bar 29 which extends upwardly to a suitable operating mechanism which is adapted to be actuated from the outside of the tank and permit the liquid within the tank to flow through the valve and into the pipe 19. The pipe 19 is extended as clearly illustrated and terminates in the usual knuckle joint 30 which is provided with the ordinary pipe through which liquid contained in the tank is conducted when the device is in use.

A draining valve 31 is secured to the bottom of the tank and communicates with the interior of the well, this valve 31 being preferably of the ordinary globe type is adapted to form an outlet through which the liquid contained in the well may be withdrawn when it is required that repairs be made to the outlet valve, described in the above paragraph.

It will be clearly seen from the foregoing that when my device is in use and under ordinary circumstances the valve 14 is left open, thus permitting the liquid contained in the main part of the tank to flow into the well and out through the outlet valve 24. In its open position, the valve 14 is supported in an inclined position upon the auxiliary wall or partition 3. Should at any time it be desirable to examine or repair the outlet valve, the valve 14 is closed and the drain

valve 31 opened. It will be obvious that the liquid contained in the well will be withdrawn through the drain valve and a workman may then descend into the well to make any necessary repairs. After such repairs are made the device is again in operative condition the drain valve may be closed the valve 14 opened, and it will be obvious that the tank will again resume its normal condition.

While in the foregoing I have shown and described the preferred embodiment of my invention, I wish it to be understood that I may change the specific arrangement of parts without in any way departing from the spirit and scope of my invention.

What I claim is:

In a device of the character described, a tank, a vertical partition positioned in said tank and arranged relatively near the side wall thereof, side partitions extending from said vertical partition to the side wall of the tank and forming a substantially rectangular well, said well extending from the bottom of the tank to the upper edge thereof, an inlet valve arranged in one side wall of the well and connecting the same with the main body of the tank, means extending to the top of the tank for controlling the valve, an outlet valve arranged in the well at the bottom thereof, means extending to the top of the well for controlling the outlet valve, and means secured to the bottom of the tank for limiting the upward movement of said valve.

In testimony whereof I affix my signature in presence of two witnesses.

CHANELL L. SAUNDERS, SR.
